Primary Examiner — Catherine A Tuttle(74) Attorney, Agent, or Firm — The Law Offices of Konrad Sherinian, LLC(57) CLAIM

What is claimed is the ornamental design for a decorative home plate, as shown and described.

DESCRIPTION

FIG. 1 is a top perspective view showing a first embodiment of my new design for a decorative home plate; and, FIG. 2 is a top perspective view showing a second embodiment of my new design.

The dotted lines represent hatching symbolic of alternating colors and other surface features that form no part of the claimed design.
